UNITED STATES PATENT OFFICE.

IDA BROWN, OF SAN FRANCISCO, CALIFORNIA.

CORSET-STAY TIP.

1,224,597.

Specification of Letters Patent.

Patented May 1, 1917.

Application filed November 30, 1914. Serial No. 874,770.

To all whom it may concern:

Be it known that I, IDA BROWN, a citizen of the United States, residing at San Francisco, in the county of San Francisco and 5 State of California, have invented certain new and useful Improvements in Corset-Stay Tips; and I do hereby declare the following to be a full, clear, and exact description of the invention, such as will enable 10 others skilled in the art to which it appertains to make and use the same.

This invention relates to auxiliary tips for attachment to corset or dress stays, and the primary object is to provide a tip of 15 this nature which may be applied to the end of a corset or dress stay when the same wears through the cloth or fabric with which it is covered, for recovering the end of the stay and preventing the same from gouging the 20 clothes or the wearer of the corset or dress to which the stay is attached.

Another object of this invention is to attach to a strip of fabric a plurality of metallic guards or tips which have transversely 25 extending ears formed at their lower ends through which eyes are punched for attaching the tip to the corset or dress to which the stay is attached.

Another object of this invention is the 30 provision of a metallic strip which has its upper marginal end and the upper ends of its sides bent inwardly for forming a socket for receiving the protruding end of the stay.

With the foregoing and other objects in 35 view this invention consists in such novel features of construction, combination and arrangement of parts as will be hereinafter more fully described, illustrated in the accompanying drawings and claimed.

40 In describing the invention in detail reference will be had to the accompanying drawings wherein like characters designate like or corresponding parts throughout the several views, and in which:—

45 Figure 1 is a plan view of the improved corset stay tips showing a plurality of them attached to a strip, for marketing.

Fig. 2 is a view showing the rear side of a fragment of a corset stay and corset to 50 which the improved tip has been applied.

Fig. 3 is a front view of Fig. 2.

Fig. 4 is a cross sectional view on the line 4—4 of Fig. 3, and

55 Fig. 5 is a front view of the improved tip showing a pair of small or narrow stays, attached thereto.

Referring more particularly to the drawings, 1 designates a strip of fabric which has secured thereto at spaced intervals metallic tips 2. The strip of fabric 1 is wider than 60 the tips 2 and extends an equal distance upon each side of the tips as is clearly shown in Fig. 1 of the drawing.

The tips 2 are constructed of sheet metal and have their upper ends and the upper 65 ends of their sides bent upon themselves as is clearly shown at 3 to form sockets 4 for receiving the ends of corset or dress stays. The main body portion 5 of the tips 2 have 70 ears 6 and 7 projecting laterally from the sides of their lower ends, which ears are provided with openings in which are seated eyes or sleeve rivets 8 for securing the tips 2 to the fabric strip 1. The eyes or sleeve rivets 8 are crimped for securing the tips 2 to the 75 fabric strip 1.

In using the tips, the strip of fabric is cut upon the dotted line shown at 10 in Fig. 1 of the drawings for applying the tip to the end of a corset or dress stay. 80 When the stay indicated by the numeral 12 in the drawings, wears through the fabric at the end of the stay, and it is desired to cover the same to form a protection for garments which are adjacent to the corset or 85 dress stays or the fabric of which the corset or dress is formed is cut away from the end of the stay which has worn through and the stay end is inserted in the socket 4 as is clearly shown in Fig. 4 of the drawings. 90 After the stay end has been inserted in the socket 4, the tip 2 is securely stitched to the fabric 14 of which the corset or dress is formed by stitching through the eyes 8. The strip of fabric which is left attached to 95 the body 5 of the tip 2, when the strip is cut as indicated on the dotted line in Fig. 3 of the drawings, is then folded over for lying in abutting engagement with the outer face of the body portion 5 of the tip 2, and 100 bent over the end of the bent end 3 of the tip and downwardly upon the outside of the piece of fabric 15 which is positioned upon the outer side of the stay 12. The end 16 of the piece of fabric 1 is then securely 105 stitched by a whip stitch to the piece of fabric 15, and the side or edges of the strip of fabric is also securely stitched to the fabric piece 15 of the dress or corset as is clearly shown in Fig. 3 of the drawing. 110 By folding the piece of the strip of fabric 1 over the end of the tip 2 and firmly stitch-

ing the same to the fabric of which the corset or dress is formed, a neat appearing protective strip is mounted upon the end of the stay for insuring against the gouging 5 of other garments with which the end of the stay might contact. The ordinary corset tip is removed prior to the mounting of the tip thereon.

In reducing the invention to practice certain minor features of construction, combination and arrangement of parts may necessitate alterations to which the patentee is entitled provided such alterations are comprehended within the scope of what is claimed.

What is claimed is:—

In combination with a corset stay having fabric thereon, of a main body portion, a strip of fabric positioned on said body por-

tion, said body portion having its upper 20 end and the upper end of its sides bent upon itself to form a socket for receiving the end of the stay, a pair of oppositely disposed ears formed on the lower sides of the body portion and having openings therein, eye rivets extending through the openings and the strip of fabric for securing the body portion thereto, and providing means whereby thread may be passed through the rivets and fabric on the stay to secure the body portion against movement upon the end of the stay.

In testimony whereof I affix my signature in presence of two witnesses.

Mrs. IDA BROWN.
